UNITED STATES PATENT OFFICE

STEPHEN WIDMER, OF BADEN, SWITZERLAND, ASSIGNOR TO A. G. BROWN BOVERI & CIE., OF BADEN, SWITZERLAND, A JOINT-STOCK COMPANY, OF SWITZERLAND

METALLIC VAPOR RECTIFIER

Application filed October 8, 1926, Serial No. 140,404, and in Germany October 17, 1925.

This invention relates to power rectifiers of the metallic vapor type.

The general purpose of the invention is the provision of a construction which will contribute to the capacity of the rectifier for handling heavy currents at high voltages, and to the certainty, reliability and continuity of operation of such apparatus.

A specific object of the invention is the prevention of back-fires or reversals in the operation of apparatus of this type.

Another specific object is the provision of an improved construction for the handling and disposal of metallic vapor within the rectifier incident to its operation.

Other and further objects will be pointed out or indicated hereinafter, or will become apparent to one skilled in the art upon an understanding of the invention or its em- 20 ployment in practice.

For the purpose of this application I disclose herein, in diagrammatic fashion, two arrangements of apparatus illustrative of the invention, but it is to be understood that 25 these are presented for the purpose of illustration only, and are not to be construed in any fashion as having the effect of limiting the claims short of the true and most comprehensive scope of the invention in the 30 art.

In the drawing forming a part of this specification

Fig. 1 is a diagrammatic representation in the nature of a sectional elevation of a mercury vapor power rectifier; and

Fig. 2 is a similar illustration of an alternative construction.

During the operation of mercury vapor rectifiers a stream of heated mercury vapor 40 is given off from the cathode and tends to spread out or expand upwardly throughout the rectifier cylinder or casing. This vapor eventually is condensed on the cooled walls and cover of the rectifier, forming drops of 45 liquid mercury which flow back to the cathode pool. It is desirable that as low a vacuum as possible be maintained within the rectifier cylinder, as the lower the vacuum, the less the likelihood of the occurrence 50 of back-fires. The production of the mer-

cury vapor, however, tends to produce a certain pressure in diminution of the vacuum. The stream of mercury vapor, moreover, tends to carry any particles of dust or particles of mercury which may be in 55 the rectifier toward the anodes, the impingement of which upon the anodes is sometimes productive of back-fires. The falling drops of condensed mercury also may cause 60 splashes which may project particles of the liquid against the anodes, with like result.

The present invention is designed to eliminate or minimize these occurrences by restricting the path of the mercury vapor stream and by directing it to portions of the 65 apparatus wherein it may be quickly condensed and from which it may be returned to the cathode pool in such fashion as to avoid the contingencies above mentioned.

The nature of the invention will be understood by reference to the illustrative diagrams wherein the reference character 10 designates the cylinder or casing of the 70 rectifier, the same being surmounted by and in communication with a condensing dome 75 11, to the upper portion of which is connected a vacuum pump 12. The cathode pool is indicated by the reference character 14, and the anodes by the numeral 15. There is a plurality of these anodes, distributed 80 about the vertical axis of the cylinder.

Spaced from the bottom of the cylinder is a dish-like shield 16 supported on insulators 17. Extending down from the top of the cylinder and encompassing the opening therefrom into the condensing dome 11 is an upwardly flaring frustro-conical receiver 18, which is open at its lower end over the cathode pool 14. Inside the lower end of the receiver 18 is formed a gutter 19 90 for the reception of liquid from the sloping interior walls thereof, and from this gutter leads off a pipe 20 which passes through the bottom shield 16 and discharges between it and the bottom of the casing. 95 Within the receiver 18 and adjacent the walls thereof, is a cooling coil 21 which is supplied with cooling liquid from an exterior source through the connection 22. Mounted on the bottom shield 16 and open- 100

ing therethrough over the cathode pool 14 is a guide funnel 24 which extends upwardly in flaring contour into close association with the opening in the lower end of the receiver 18, the lower end of said guide funnel terminating close to the receptacle in which the cathode pool is contained.

The walls of the cylinder 10 and of the condensing dome 11 may be cooled by liquid circulated in the water jacket portions 10 25 and 26.

In the operation of the device, the mercury vapor which rises from the cathode 14 at a moderately high pressure is directed 15 through the guide funnel 24 into the receiver 18. As the funnel 24 and receiver 18 flare upwardly, they afford the necessary volume for the expansion of the mercury vapor. The vapor is condensed on the coil 21 and 20 the adjacent wall of the receiver 18 and within the condensing dome 11, thus preventing the building up of a pressure in the receiver which might tend to force some of the mercury vapor out into the space about 25 the anodes, and the operation of the vacuum pump 12 likewise functions to prevent the building up of a pressure within the receiver. As a result, the mercury vapor is effectively guided and confined away from 30 the anodes, in such fashion that the latter are not subjected to the blast thereof. The mercury which condenses on the cooled surfaces is caught in the gutter 19 and conducted back by the pipe 20 below the shield 35 16, and returned to the cathode pool without opportunity for its being impinged on any surfaces where it may be splashed or partly vaporized and particles impelled against the anodes. The pipe 20 may be so 40 arranged that it will draw off from the gutter 19 only the mercury, leaving all the impurities behind in the gutter.

In the construction illustrated in Fig. 2 the arrangement is substantially the same 45 excepting that the receiver 18 is cooled by liquid circulated within a water jacket 27 which encompasses it, instead of through a condensing coil as in the first instance.

By virtue of the invention, various occurrences productive of back-fires are eliminated or minimized, and the ability of the apparatus for the handling of heavy currents over extended periods of time with certainty and reliability, is thereby increased.

What I claim is:

1. In rectifying apparatus of the character described, a casing, anodes spaced with respect to each other and disposed in said 60 casing, a vapor-emitting cathode disposed in said casing, means providing a vapor-condensing chamber, means operable to direct the vapor stream from said cathode into said chamber out of direct contact with 65 said anodes, said directing means including

funnel-shaped elements each increasing in cross-sectional area from substantially one end to the other end thereof, said elements being supported in coextensive arrangement with respect to each other with the smaller end of one element disposed adjacent said cathode in such manner as to receive the vapor stream issuing therefrom and with its larger end disposed adjacent to and spaced from the smaller end of the adjacent element, one of said elements being supported with its larger end in direct communicating relation with said chamber, and means associated with one of said elements and operable to provide for return flow from the same back to said cathode of operating fluid emitted from said cathode incident to operation of said apparatus.

2. In rectifying apparatus of the character described, a casing, anodes spaced with respect to each other and disposed in said casing, a vapor-emitting cathode disposed in said casing, means providing a vapor-condensing chamber, means operable to direct the vapor stream from said cathode into said chamber out of direct contact with said anodes and including a funnel-shaped element increasing in cross-sectional area from substantially one end to the other end thereof and supported with its larger end in direct communicating relation with said chamber, said element being provided at substantially its smaller end with a vapor-condensate collecting trap opening into said element, and means providing a return vapor-condensate connection from said trap at a point elevated from the bottom thereof to said cathode.

In testimony whereof I have hereunto subscribed my name at Zurich, Switzerland, 105 on the 22 day of September, A. D. 1926.

STEPHEN WIDMER.
